CYLINDER TISSUE PAPER MACHINE

Estel B. Geary, Niles, Mich.

Application June 20, 1950, Serial No. 169,157

2 Claims. (Cl. 92—43)

1

This invention relates to paper making, and more particularly to a machine for forming, drying and collecting a web of paper.

A main object of the invention is to provide a novel and improved apparatus for making paper, said apparatus being very simple in construction, eliminating the need for excessive pressure on the paper web, providing a stronger paper web with less cost, providing increased speed of production of paper as compared with machines of the prior art, and being very economical to operate.

A further object of the invention is to provide an improved paper-making machine of the type employing felt webs for drying the formed paper web, the machine providing a drying action of the paper web without requiring pressure on the felt webs, requiring less heat to dry the paper web than in machines of the prior art, improving the durability of the felt webs, providing improved and more efficient means for drying the felt webs than employed in the prior art, reducing the amount of vibration involved, reducing the amount of slipping of the paper web as it is processed, preventing the crushing of the paper web, providing an efficient preliminary drying of the paper web as it is fed to the collecting rolls, whereby less heat will be required to dry the paper web to its finally completed condition than in the prior art apparatus, and providing a stronger and more uniform resultant paper product.

Further objects and advantages of the invention will become apparent from the following description and claims, and from the accompanying drawings, wherein the single figure is a side elevational view, partly in longitudinal cross-section, illustrating an improved paper-making machine constructed in accordance with the present invention.

Referring to the drawings, 24 designates a vat connected by conduit means, not shown, to a source of paper stock liquor. Rotatably mounted in vat 24 and connected to a suitable driving motor is a paper web-forming roll 8 of conventional construction, which may comprise, for example, a cylindrical screen, as employed in the Fourdrinier-type of paper-making machine. The vat 24 contains a block member 25 formed to extend around the lower surface portion of roll 8 and being spaced therefrom to define a flow channel for paper stock liquor from the left side of the roll to the right side thereof, as viewed in the figure. The block 25 has an overflow edge at 26, over which stock liquor may flow for recirculation 50 and being spaced therefrom to define a flow channel for paper stock liquor from the left side of the roll to the right side thereof, as viewed in the figure. The block 25 has an overflow edge at 26, over which stock liquor may flow for recirculation

2

in the vat. Recirculation is produced by a pump 27 disposed in a conduit 28 connecting the right-end portion of the vat to the left-end portion thereof, as shown.

5 The liquor carrying the paper stock passes through the screened roll 8, whereby the stock forms on the surface of the roll. The roll rotates faster than the movement of the liquor below and through the roll, whereby the paper fibres are 10 caused to lie flat against the face of the roll. The liquid passing through the cylinder 9 flows back to the circulation passage beneath the cylinder by gravity through openings in the ends of the cylinder 9. As mentioned above, roll 8 is of 15 standard construction.

Designated generally at 29 is a frame located adjacent the vat 24. Rotatably mounted on frame 29 above vat 24 are a plurality of web carrying rolls 1 to 6 which are arranged in parallel spaced 20 relation and are disposed in the same horizontal plane and connected to suitable driving means. Rotatably supported on frame 29 forwardly adjacent the upper portion of roll 8 is the couch roll 7. Designated at 9, 10, 11, 12 and 13 are 25 respective rolls rotatably supported on frame 29. It will be noted that roll 9 is a first guiding roll and is disposed above and rearwardly of roll 8, rolls 10 and 11, second and third guiding rolls respectively, are disposed below and rearwardly of roll 9 and roll 13 is a first additional web carrying roll and is disposed substantially in the same plane as rolls 1 to 6 and adjacent the rear end of 30 frame 29. Each of rolls 7, 9, 10, 11, 12 and 13 is 35 coupled to driving means which rotates said rolls synchronously with rolls 1 to 6. Roll 12 is a first stretching roll and is movable horizontally toward and away from the roll 8, the roll 12 being mounted on a slidble bearing 30 which may be 40 adjusted horizontally on frame 29 by means of a manually operated adjusting screw 31 rotated by a handwheel 32. Mounted on the rolls 1 to 7 and rolls 9 to 13 is a felt web 33. The tension of endless web 33 may be regulated by means of handwheel 32. It will be noted that web 33 passes 45 alternately over and under the rolls 1 to 6, over roll 13, around roll 12, over roll 11, under roll 10, over roll 9 and around couch roll 7, said web being driven in the direction indicated by the arrow above couch roll 7.

Designated respectively at 14, 15 and 16 are 50 additional rolls rotatably supported on frame 29 above rolls 1 to 6. Roll 15 is a second stretching roll and is movable vertically toward and away from rolls 1 to 6, the roll 15 being provided with a vertically adjustable bearing 34 whose position

may be varied by means of a screw 35 operated by a handwheel 36. Roll 16 is a second additional web carrying roll and is disposed above the roll 3. Roll 14 is a third additional web carrying roll positioned between rolls 4 and 5 and is movable vertically toward and away from the roll 13, the roll 14 being mounted on a vertically adjustable bracket 37 whose position may be varied by a screw 38 operated by a handwheel 39. Designated at 40 is a second endless felt web extending alternately under and over the rolls 2 to 6, around roll 14, under roll 15 and over roll 16. Rolls 14 to 16 are driven, by means not shown, synchronously with rolls 2 to 6. The tension of web 40 may be adjusted by means of the handwheel 36.

Designated at 17 is the paper-collecting roll, said roll being rotatably mounted on the rear end of frame 29 subadjacent roll 14. The position of roll 14 relative to roll 17 may be adjusted by means of the handwheel 39.

Web 40 is driven in the direction indicated by the arrow above roll 2, whereby webs 33 and 40 travel in the same direction past the rolls 2 to 6.

Each of the rolls 1 to 7, 9 to 13, 15 and 16 is provided with a pair of internal suction nozzles 41, 41 connected to a suitable vacuum pump. The rolls are perforated and the suction nozzles act to draw moisture through the perforated surfaces of the rolls from the webs engaged thereon. Designated at 18 to 23 are respective sprinkler heads connected to a suitable water supply. First sprinkler head 18 is mounted above web 40 between rolls 14 and 15. Second sprinkler head 19 is mounted below web 33 between rolls 6 and 13. Third sprinkler head 20 is mounted below web 33 between rolls 12 and 13. Fourth sprinkler head 21 is mounted below web 33 between rolls 11 and 12. Fifth sprinkler head 22 is mounted above web 33 between rolls 10 and 11. Sixth sprinkler head 23 is mounted below web 33 between rolls 9 and 10.

In operation, the paper web formed on roll 8 is picked up by the felt web 33 by the vacuum of couch roll 7 and is carried over roll 1 and thence between the felt webs 33 and 40 past rolls 2 to 6. The suction nozzles in couch roll 7 remove a substantial amount of water from the paper web. The suction nozzles in the rolls 1 to 6 also remove water from the paper web whereby the web is continuously dried as it passes the rolls 1 to 6. As the paper web passes roll 6, it travels with felt web 40 toward the roll 14 and engages on the collecting roll 17, which removes the paper web for further drying.

The upper felt web 40 then passes around roll 14 and is washed by the sprinkler head 18.

The lower felt web 33 is first washed from below by sprinkler head 19. Moisture is then removed from felt web 33 by relatively low vacuum suction in roller 13. The face of web 33 is then further washed by sprinkler 20 and moisture is removed from the web by relatively high vacuum in roll 12. The felt web 33 is then again washed by sprinkler 21 and moisture is then removed from the felt by moderate vacuum in roller 11. Web 33 is then again washed by sprinkler 22 and moisture is removed therefrom by moderate vacuum in roll 10. The face of web 33 is then again washed by sprinkler 23 and moisture is removed from the web by high vacuum in roll 9.

The above cycles of washing and vacuum completely loosen and remove all the dirt and loose particles from the felt webs without mechani-

cally damaging the webs or causing undue wear thereon.

The machine operates without vibration and without compressing or excessively squeezing the paper web as it passes between the felt webs 40 and 33. The felt webs will be kept clean, so that water will not be pulled through dirt or filth, and the felts will not become clogged, since all loose material will be removed therefrom by the above-described cycles of washing and vacuum cleaning.

Since the water is removed from the paper web without appreciable squeezing pressure, the felt webs will not be subject to excessive wear and will be easy to keep clean. Furthermore, particles of hard material passing between the felt webs will not damage the webs to any serious extent.

While a specific embodiment of a paper-making machine has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A paper-making machine comprising a vat, means circulating paper stock liquor through said vat, a horizontally disposed perforated web forming roll rotatably mounted within said vat, a perforated horizontally disposed rotary couch roll positioned adjacent the upper peripheral portion of said web forming roll, a plurality of perforated web carrying rotary rolls arranged in parallel spaced relation positioned in a horizontal plane spaced above said couch roll, a first horizontally disposed guiding rotary perforated roll positioned above and rearwardly of said perforated web forming roll, second and third horizontally disposed rotary perforated guiding rolls spaced from each other positioned below and spaced from said plurality of web carrying rolls and rearwardly of and spaced from said first guiding roll, a first horizontally disposed additional web carrying rotary perforated roll positioned rearwardly of and spaced from said plurality of web carrying rolls and in substantially the same horizontal plane in which the latter named rolls are disposed, a first horizontally disposed stretching rotary roll positioned between and spaced from said plurality of web carrying rolls and said second and third guiding rolls, a first endless felt web engaged over said couch roll and alternately over and under successive ones of said plurality of web carrying rolls and engaged respectively over said first additional web carrying roll, said first stretching roll, said second and third guiding rolls and said first guiding roll, a second horizontally disposed additional web carrying rotary perforated roll disposed above and spaced from said plurality of web carrying rolls and inwardly of said first guiding roll, a third horizontally disposed additional web carrying roll positioned above and spaced from said first additional web carrying roll, a second horizontally disposed stretching rotary perforated roll positioned between and spaced from said plurality of web carrying rolls and said second and third additional web carrying rolls, a second endless felt web engaged over said second and third additional web carrying rolls and said second stretching roll and alternately over and under successive ones of said plurality of web carrying rolls, a rotary paper collecting roll positioned below and adjacent to said third additional web carrying roll, suction nozzles

in said couch roll, in each of said plurality of web carrying rolls, in each of said first, second and third guiding rolls, in each of said first and second stretching rolls, and in each of said first and second additional web carrying rolls, a first sprinkler head positioned above said second felt web between said second and third additional web carrying rolls, a second sprinkler head positioned below said first felt web between said first additional web carrying roll and the adjacent one of said plurality of web carrying rolls, a third sprinkler head positioned below said first felt web between said first additional web carrying roll and said first stretching roll, a fourth sprinkler head positioned below said first felt web between said first stretching roll and said third guiding roll, a fifth sprinkler head positioned above said first felt web between said third and second guiding rolls, and a sixth sprinkler head positioned below said first felt web between said second and first guiding rolls.

2. A papermaking machine comprising a vat, means circulating paper stock liquor through said vat, a horizontally disposed perforated web forming roll rotatably mounted within said vat, a perforated horizontally disposed rotary couch roll positioned adjacent the upper peripheral portion of said web forming roll, a plurality of perforated web carrying rotary rolls arranged in parallel spaced relation positioned in a horizontal plane spaced above said couch roll, a first horizontally disposed guiding rotary perforated roll positioned above and rearwardly of said perforated web forming roll, second and third horizontally disposed rotary perforated guiding rolls spaced from each other positioned below and spaced from said plurality of web carrying rolls and rearwardly of and spaced from said first guiding roll, a first horizontally disposed additional web carrying rotary perforated roll positioned rearwardly of and spaced from said plurality of web carrying rolls and in substantially the same horizontal plane in which the latter named rolls are disposed, a first horizontally disposed stretching rotary roll positioned between and spaced from said plurality of web carrying rolls and said second and third guiding rolls and movable toward and away from said perforated web forming roll, a first endless felt web engaged over said couch roll and alternately over and under successive ones of said plurality of web carrying rolls and engaged respectively over said first additional web carrying roll said first stretching roll said second and third guiding rolls and said first guiding roll, a second horizontally disposed additional web carrying rotary perforated roll disposed above and spaced from said plurality of web carrying rolls and inwardly of said first guiding roll, a third horizontally disposed additional web carrying roll posi-

tioned above and spaced from said first additional web carrying roll and movable vertically toward and away from said first additional web carrying roll, a second horizontally disposed stretching rotary perforated roll positioned between and spaced from said plurality of web carrying rolls and said second and third additional web carrying rolls and movable vertically toward and away from said plurality of web carrying rolls, a second endless felt web engaged over said second and third additional web carrying rolls and said second stretching roll and alternately over and under successive ones of said plurality of web carrying rolls, a rotary paper collecting roll positioned below and adjacent to said third additional web carrying roll, suction nozzles in said couch roll, in each of said plurality of web carrying rolls, in each of said first second and third guiding rolls, in each of said first and second stretching rolls, and in each of said first and second additional web carrying rolls, a first sprinkler head positioned above said second felt web between said second and third additional web carrying rolls, a second sprinkler head positioned below said first felt web between said first additional web carrying roll and the adjacent one of said plurality of web carrying rolls, a third sprinkler head positioned below said first felt web between said first additional web carrying roll and said first stretching roll, a fourth sprinkler head positioned below said first felt web between said first stretching roll and said third guiding roll, a fifth sprinkler head positioned above said first felt web between said third and second guiding rolls, and a sixth sprinkler head positioned below said first felt web between said second and first guiding rolls.
